BRACKET FOR BURGLAR ALARMS

Jesse L. Gempp, Los Angeles, Calif.

Application April 26, 1948, Serial No. 23,172

2 Claims. (Cl. 200—54)

1

This invention relates to a new and novel bracket means for holding the flexible arm of a burglar alarm switch in open position, but allowing the switch to close when the bracket means is shifted away from the arm. Other kinds of crude brackets have been heretofore employed, but the bracket of this invention is a much needed improvement over all prior ones.

One of the principal objects of this invention is to present a dependable and adjustable bracket means which cooperates with and operates the switch arm of a well known burglar alarm device which is attached to doorways, windows, and other openings to be automatically guarded.

Another object is to provide a bracket means which is adapted for operating a burglar alarm switch which is simple and sturdy in construction, easy to install and operate, and which is economical to make and manufacture.

Other objects, advantages and features of this invention will appear from a perusal of the accompanying drawings, the subjoined detailed description, the preamble of these specifications, and the appended claims.

Applicant is now about to describe one of the preferable forms of his invention in order to teach one how to make and use the same, but it is to be understood that the drawings and description thereof are not to limit the invention in any sense whatsoever except as specifically limited by the appended claims.

In the drawings:

Figure 1 is an elevational view of the top portion of a door and the trim surrounding the doorway which includes the invented bracket means fixed to the top of the door and the burglar alarm switch fixed to the top trim of the doorway.

Figure 2 is an enlarged view taken substantially along the line 2—2 of Figure 1.

Figure 3 is an enlarged plan view of the burglar alarm switch and the bracket means, this view showing the door partly opened and the switch closed.

Figure 4 is a sectional view taken substantially along the line 4—4 of Figure 2.

As clearly shown in the drawings, a doorway is illustrated in part and has the usual side trims 1 and 2, and the top trim 3. A door 4 is shown having one side edge thereof hinged, the top hinge 5 being shown only. The burglar alarm switch includes a single integral bar member having the straight portion 6 which is securely fixed to the top trim by any suitable means such as screws and

2

the like. One end of this straight portion is bent away from the door trim to provide the arm 7 which is again bent to form the short arm 8 and the contact finger 9, this finger 9 being shaped and adapted to make good electrical contact with a flexible switch arm 10. This arm 10 is held in position by the screws 11 and 12 which screws also hold the bar member 6 securely to the trim 3. These screws are insulated from the member 6 and the switch arm 10 so that these parts are not a single electrical conductor. To insure the insulation of these parts from one another, an insulation sheet or strip 13 is inserted between them in the well known manner.

From the bar member 6 leads an insulated electrical conductor 14 and from the flexible arm 10 leads another insulated electrical conductor 15, these conductors not only have the switch arm 10 and bar member 6 in series, but also a source of suitable electric current and one or more fire or burglar alarms situated at predetermined places. Thus, when the switch arm 10 makes contact with the finger 9, the circuit is closed and the alarm sounded. All the foregoing parts are well known and are given in order to show how the invention is applied thereto.

The bracket means of this invention is indicated in general by the reference character 16 and consists of a base or main support item having the outstanding sleeve portion 17 which is integral with the opposite directed flanges 18 and 19 that are attached securely to the top of the door 4 by screws. The base has a hole 20 which allows the head of an adjustable screw 21 to pass therethrough.

The sleeve 17 has a squared bore 22 which snugly accommodates the element 23 which has a squared cross-section and which is freely slideable through the bore 22 when in a released condition. Note, that the adjustable screw 21 is threaded into the inner end of the element 23, and that this screw can be set so as to limit the distance that the element can be forced into the sleeve 17.

The element 23 has an integral extending rod 24 that is adapted to engage the switch arm 10 and free the end thereof from the contact finger 9 when the door is in a closed position. The element 23 has a slot or groove 25 which accommodates the stem of a screw 26 that is threaded through one side of the sleeve 17. This screw and groove arrangement makes it possible to adjust the element 23 relative to the sleeve 17 and

hence the exact positioning of the rod 24, but should this screw ever become loose, the ends of the groove would prevent the element from being accidentally removed from its sleeve. The stop screw 21, however, will limit the inward movement of the element 23 regardless of the action of the set-screw 26.

From the foregoing, it should now be seen that applicant has provided a very useful bracket which is a definite improvement over any of the brackets heretofore employed for such purposes.

It is, of course, understood that various changes and modifications may be made in the details of form, style, design, and construction of the whole or any part of the specifically described embodiment of this invention without departing from the spirit thereof; such changes and modifications being clearly within the scope of the following claims.

I claim:

1. A bracket means for burglar alarm switches, said means comprising a base with means for attaching it firmly to a closure, a sliding means incorporated in the base and constructed with means for adjustably fixing it to the base, an arm extending from the sliding means which is adapted to engage a flexible switch arm and open an electrical circuit, a rectangular bore in the base sized to snugly receive the sliding means, the sliding means having an adjustable screw at 30

one end thereof opposite the end fixed to the arm, and a groove in the sliding means accommodating the stem of a set-screw which passes through the base at one side thereof.

5 2. A bracket means for burglar alarm switches, the bracket having a base with a square bore therein and a slidable element in the bore having a square cross-section, means for attaching the base to a closure combination, a groove in one 10 side of the element, a set screw threaded through one side of the base and having its stem in the groove, an arm extending from the element having an end adapted to compress a flexible switch arm, the end of the element opposite the 15 arm thereof having an adjustable stop screw, said screw being mounted so that the head thereof can contact the surface upon which the bracket means is attached.
